UNITED STATES PATENT OFFICE

RICHARD E. BERTHOLD, OF RICHMOND HILL, NEW YORK, ASSIGNOR TO CARDINAL PRODUCTS, INC., OF NEW YORK, N. Y., A CORPORATION OF NEW YORK

LIGHTER

Application filed January 9, 1933. Serial No. 650,911.

This invention relates to lighters of a character adapted to the purpose of igniting cigarettes and the like, and my improvements are particularly directed to a device of this nature wherein the vapor from alcohol or other vaporizable fluid, in its absorption by platinum black, or similar catalytic substances, creates incandescence in a body or block thereof, whereby, upon applying a cigarette end to said body, and drawing upon the cigarette, the resulting incandescence enables ignition of the cigarette to be effected.

The lighter consists of a casing containing an absorbent which is charged with a vaporizable fluid (pure methanol alcohol giving excellent results), and a block or body of platinum black, spongy platinum, or the like, is disposed at the outer end of the casing, being suitably supported in position to collect the vapor, means also being provided for creating a current of air that will assist the flow of vapor to the catalytic element.

The casing contains a removable holder, in which is fitted an annulus composed of a suitable substance, such for example as meerschaum, which forms a seat for a block of platinum black or other catalytic material that is suitably supported in the holder and has a convex surface which is exposed through the annulus and enables contact to be had therewith by a cigarette end, for ignition.

Also means are provided for the admission of air to the rear of the block of catalytic material, and a removable cap is adapted to fit the casing for the purpose of enclosing the block of catalytic material, and the air admission means, when the lighter is not in use.

Other features and advantages of my invention will hereinafter appear.

Figure 1 is an enlarged, sectional elevation of my improved lighter.

Fig. 2 is a section on the line 2—2 of Fig. 1, and

Fig. 3 is an elevation of the lighter, with parts broken away, the cover being removed.

In said figures let 1 indicate a tubular casing, and 2 a tubular insert or holder, which is adapted to be removably, though snugly fitted within said casing, said holder 2 and

the casing having co-acting means to limit the extent to which the holder can be inserted in the casing, and to localize the holder in the casing so that the upper portion of the holder may project a suitable distance beyond the casing. As an example of such limiting and localizing means the casing is shown as provided with a curved slot 3 that extends inwardly from the casing perimeter, and the holder 2 is provided with a projection 4 which is adapted to engage said slot in the manner of a bayonet joint to effect the localizing engagement. The outer end of the holder is knurled, as at 5, for firm finger grasp in the operation of turning the holder, within the casing, while making and releasing the joint.

The casing is provided with an external, annular shoulder 6, and a cap 7, which is adapted to snugly and telescopically slide over the upper portion of said casing, finds its seat upon said shoulder and thus is limited and localized in its fitted relation upon the casing.

The holder 2 is provided, at its outer end, with an inturned flange 8, which may be angled, as shown, and an annulus 9, which may be composed of meerschaum, or other suitable substance or material that is capable of resisting the effects of heat, is placed within the holder and confined therein by contact of its outer surface with the flange 8. The said outer surface of the annulus may be angled like the flange 8, to fit snugly thereagainst, but the lower portion of the annulus is recessed, as at 10, for a purpose which will be described hereinafter.

As premised, my invention comprehends the use of a block of catalytic material, such as platinum black, or spongy platinum, which I employ as an igniting element in the lighter in the form of a pellet or tablet, so located and held at the open end of the holder that when such element is rendered incandescent by the presence of alcoholic vapor and atmospheric air, a cigarette or the like may be ignited by placing the end thereof in physical contact with said element.

The igniting element, here indicated at 11, is as stated in the form of a tablet, having

been moulded under pressure and given a convex contour at its outer surface 12, where it is to be exposed through the annulus 9, the shoulder 13 produced by the recess 10 in the annulus, overhanging the outer peripheral edge portion of element 11 to confine the latter forwardly. The element 11 is provided with an aperture therethrough, here shown at 14 as located axially thereof.

10 Fitted within the holder, beneath the element 11, is a washer 15, having a relatively large central opening 16 therethrough, and also fitted within the holder, beneath washer 15, is a disk 17, said washer and disk being in spaced relation, the extent of the spacing between said washer and disk being determined by a spacer of suitable thickness. The spacing element here shown is indicated at 18 and is composed of a piece of wire shaped like the letter S. The particular spacing is such as to provide a chamber of appropriate capacity, access by atmospheric air being had thereto by holes 19 through the wall of the holder and communicating only with said chamber.

It will be appreciated that the fit of the disk 17 within the holder must be sufficiently snug so that said disk may form a rearward support for the other members contained between it and the flange 8.

30 The disk 17 is composed of meerschaum or other suitable substance or material which is sufficiently porous to be permeable by vaporizable fluid. The washer 15 may be of similar material.

35 Fitted within the holder 2, from its lower end, is a piece of wicking 20 or other suitable absorbent material, a portion of said wicking projecting outside the holder and being adapted to be entered within the casing in the act of fitting the holder in the casing. It is intended that the exposed portion of the wicking shall be dipped in alcohol or other suitable vaporizable fluid, to become saturated therewith, before fitting the holder to the casing. A piece of absorbent material 21, at the bottom of the casing will serve to absorb any surplus fluid from wicking 20.

40 The wicking 20 is here shown as bound, 50 in cylindrical form, by tie strands 22, because, while said wicking is to be held permanently in the holder 2, the projecting portion of said wicking has to be removed, with the holder, from the casing, each time the wicking is to be saturated with vaporizable fluid, and it is desirable that the bulk of the wicking be confined to facilitate the act of re-inserting it in the casing. The incised tongues 23 in the holder wall are bent into engagement with 55 the wicking to retain the latter.

55 In the practical embodiment of my invention herein described and illustrated certain important considerations have been observed and have resulted in the provision of these 60 essential features:

(1) The saturated wicking is in contact with the permeable disk which separates the igniting element from the fluid.

(2) A chamber of definite capacity separates the permeable disk from the aperture washer that supports the igniting element; 70 said chamber having admission ports for atmospheric air, and constituting an air and fuel mixing chamber.

(3) The igniting element is apertured for 75 fluid flow.

(4) The fit of the cap 7 upon the casing is sufficiently tight to prevent the entry of air and to permit the creation of a strong suction effect, in pulling off the cap, which draws the 80 gaseous mixture against the igniting element, for absorption thereby, resulting in the igniting incandescence of said element.

This application is a continuation in part 85 of my earlier application, Serial No. 620,795, filed July 5, 1932, for lighters.

Variations within the spirit and scope of 90 my invention are equally comprehended by the foregoing disclosure.

I claim:—

1. A lighter comprising a casing adapted to contain vaporizable fluid, a holder in said casing and a block of catalytic material supported by said holder in the path of vapor from said fluid, a surface of said block being exposed for contact with a cigarette or the like, said holder being provided with means for the admission of air to the opposite surface of said block.

2. A lighter comprising a casing adapted to contain vaporizable fluid, a holder in said casing and a block of catalytic material supported by said holder in the path of vapor from said fluid, a surface of said block being exposed for contact with a cigarette or the like, said holder being provided with means for the admission of air to the opposite surface of said block, and removable closure means for said casing adapted to cover said block and air admission means.

3. A lighter comprising a casing adapted to contain vaporizable fluid, a holder in said casing and a block of catalytic material supported by said holder in the path of vapor from said fluid, said block being apertured and having a surface exposed for contact with a cigarette or the like, said holder being provided with means for the admission of air to the opposite surface of said block.

4. A lighter comprising a casing adapted to contain vaporizable fluid, a holder in said casing and a block of catalytic material supported by said holder in the path of vapor from said fluid, said block being apertured and having a surface exposed for contact with a cigarette or the like, said holder being provided with means for the admission of air to the opposite surface of said block, and removable closure means for said casing adapted to cover said block and air admission means.
